UNITED STATES PATENT OFFICE

2,004,113

TANK

George T. Horton, Chicago, Ill.

Application October 5, 1933, Serial No. 692,336

3 Claims. (Cl. 220—1)

This invention relates to improvements in high and low pressure tanks, and vacuum tanks, and, more especially, to sheet metal tanks. My invention is applicable, for example, for use in connection with such tanks for the storage of volatile oils where it is necessary or desirable to maintain a certain amount of vapor pressure inside of the tank in order to reduce losses of evaporation.

By the use of my invention there is effected a marked saving in material, labor and space. My invention permits the use of relatively thin sheet metal in the heads of the tank, since each section is curved so that most of the stress will be a tensional one.

Another feature of this invention is the provision of means to enable the support of the tank upon a sand foundation.

Other features and advantages of my invention will appear more fully as I proceed with my specification.

In that form of device embodying the features of my invention shown in the accompanying drawings—

Figure 1 is a view in side elevation with a portion of the shell being broken away; Fig. 2 is a view partly in plan and partly in horizontal section; Fig. 3 is a view taken as indicated by the line 3 of Fig. 2; Fig. 4 is a view taken as indicated by the line 4 of Fig. 3; and Fig. 5 is a view taken as indicated by the line 5 of Fig. 3.

As shown in the drawings, the pressure tank includes a shell 10, here shown as cylindrical and placed in a vertical position so that the two heads may be referred to as upper and lower heads.

These heads in general are flat. The shell 10 need not be perfectly or exactly cylindrical but, for example, may be scalloped, as shown in United States Patents Nos. 1,668,179; 1,864,759; and 1,864,931. The two heads of the tank are here shown as formed of radially arranged sector-shaped sheet metal sections. As here shown, these sections are curved or convexed outwardly, being substantially conical sections or segments of a cone formed by making sectional cuts through the apex and base of a cone. It is obvious, however, that conical sections need not be employed.

For example, the sections could be sections of a cylinder instead of sections of a cone. The particular feature is to curve or convex the same outwardly so that there will be imposed upon the same a tensional stress. Such curving or convexing is circumferential and not radial. The sections forming the upper head are indicated by 11, 11 and those forming the lower head are indicated by 12, 12.

The sections of the heads do not extend to an extreme point at their inner ends but are cut off to permit the insertion in the center of a central vertical pipe member 13 provided with the upper enlarged end 13^a and the lower enlarged end 13^b. The ends of this member are closed by the upper curved cap member 13^c and the lower curved cap member 13^d and the same is provided with holes 13^e and 13^f at its upper and lower ends, respectively, so that the interior of the same will be in communication with the interior of the tank. In this way the entire central pipe member with its enlarged ends is utilized for storage and, consequently, the capacity of the entire tank is not diminished by the insertion of this pipe member.

The tank is provided with bracing members in the form of tension members between the heads, said tension members being fastened to the heads substantially at the junction of the conical sections. As here shown, these tension members take the form of angle irons 14 having their upper ends connected to the radial I-beams 15^a which are connected to the upper head along the junction lines between the adjacent sectors thereof on the inside of the tank. The lower ends of the members 14 are similarly joined to I-beams 15^b fastened to the inside of the lower head.

The upper edge of the cylindrical shell is here shown as scalloped, as indicated by 10^a, to conform to the curvature of the upper head sections 11; and the troughs formed on top of the roof between the junctions of the upper head sections may be sloped to drain outwardly.

The lower edge of the cylindrical shell, as indicated by 10^b, is left straight and its extreme lower edge lies below the lowest point of any of the sections 12. By this construction, the depending edge 10^b of the shell forms a skirt around the lower head. This skirt is utilized to assist in holding sand 50 or similar material under the tank which serves as a foundation for the same. For example, the sand 50 is graded to substantially conform to the sectors 12, 12 of the lower head. The tank is then built upon this sand and the skirt 10^b at the lower edge of the shell prevents escape of the sand outwardly.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my

invention as broadly as permissible, in view of the prior art.

What I regard as new, and desire to secure by Letters Patent, is:

- 5 1. A sheet metal tank including a substantially cylindrical shell with a generally flat lower head formed of radially arranged sector-shaped sheet metal sections, said sections being circumferentially convexed, whereby the differences in pressure 10 between the inside and the outside of the tank will impose tensional stresses on said sections, the lower edge of said shell extending substantially below the lowest point of the sections in the lower head to serve as a retaining wall for the foundation under the tank between 15 the lower portions of the sections.

2. A sheet metal tank including a substantially cylindrical shell with generally flat heads formed of radially arranged sector-shaped sheet metal sections, said sections being circumferentially convexed, whereby the differences in pressure 5 between the inside and the outside of the tank will impose tensional stresses on said sections, and a central pipe with closed ends joining the heads, said pipe being provided with apertures to afford communication between its interior and 10 the interior of the tank.

3. A tank as claimed in claim 2, with bracing members between the heads, said bracing members being fastened to the heads substantially at the junction of the sector-shaped sections. 15

GEORGE T. HORTON.
